[57] CLAIM

The ornamental design for a lavatory, as shown and described.

DESCRIPTION

FIG. 1 is a top left perspective view of a lavatory showing our new design;

FIG. 2 is a top plan view thereof;

FIG. 3 is a cross sectional view taken along line 3—3 of FIG. 2; and

FIG. 4 is a cross sectional view taken along line 4—4 of FIG. 2.

The broken line representations of holes in FIGS. 1 and 2 and the fragmentary broken line representation of a countertop in FIG. 1 are for purposes of illustration only and form no part of the claimed design.

FIG. 1

FIG. 2

FIG. 3

FIG. 4
